WEATHER STRIP AND SASH BALANCE

Anthony J. Ricci, Yeadon, Pa.

Application July 23, 1941, Serial No. 403,641

4 Claims. (Cl. 20—52)

This invention relates to a combined weather-strip and balance for window sash, and it has for its primary object the provision of a simple, inexpensive and effective device of this character, which, in addition, simplifies and renders less expensive, the frame for the windows.

How the foregoing, together with such other objects and advantages as may be incident to the invention are realized, is illustrated in the accompanying drawing, wherein—

Figure 1 is a fragmentary section through window framing and window sashes, taken on the line 1—1 of Figure 2, and

Figure 2 is a similar section taken on the line 2—2 of Figure 1.

In the drawing the parts are shown in full size. The reference numeral 7 indicates one of the jambs of the window frame, the reference numeral 8 the lower sash, and the reference numeral 9 the upper sash.

The upright or side members 8a and 9a of each sash are provided with grooves 10, flattened at 11 at the sides, and rounded at 12 at the base. It will be understood that each sash is provided with such a groove at each of its two upright side portions.

The combined weather strip and sash balance is indicated as a whole by the reference character A. This device is preferably made from a single strip of sheet metal, bent into the shape shown in the drawing. It will be seen that portions of the blank strip are rebent inwardly on themselves, providing wing portions indicated at 13, and then into semi-cylindrical portions 14, the free edges of which overlap as shown at 15. The semi-cylindrical portions 14 thus, in effect, constitute a cylindrical tube which fits within the groove 10. The diameter of this tubular portion is normally greater than the distance between the two flattened surfaces of the groove. The combined weather strip and balance is made of a metal such as bronze, which has sufficient springiness to allow the tubular portion to collapse somewhat on insertion into the groove. This collapse occurs because the overlapping edge portions of the semi-cylindrical parts 14 can slip on one another. Because of the springiness of this metal, the portions 14 bear against the flattened surfaces of the groove with sufficient pressure to cause the device to also act as a balance holding the sash in any given position of adjustment, and at the same time affording effective weather strip action. The bronze is also resistant to weather.

It will be understood that the combined 55

weather strip and balance runs for substantially the full height of the jambs. In assemblage, the combined strip and balance devices are inserted in the grooves and the sashes are then put in place in the framing. The devices are nailed or otherwise secured to the jambs through the wing portions. This can be done in a very simple manner. With the upper sash in position, the lower portion of the combined strip and balance 10 is exposed and can be tacked, after which the sash is lowered, and the upper portion of the strip and balance is tacked. Similarly with the lower sash. The trim 16 is then put on.

It will be seen that the device dispenses with 15 the sash cord and weights ordinarily employed, and likewise simplifies the frame structure.

It will be noted that the depth of the tubular portion is such as to provide a substantial clearance between the inner face of the tubular portion 20 and the rounded base portions 12 of the groove. Thus, swelling of the sash does not cause the sash to bind or lock on the tubular portions. Swelling of the sash such as tends to cause inward pressure of the sides of the grooves 25 on the tubular portion can cause no difficulty because of the overlapping of the free edge portions of the parts 14. The weather—snow, rain, ice—is substantially excluded from the interior of the tubular portion.

It will be observed that the tubular portion 30 affords a limited area of contact on the flattened sides of the grooves. By virtue of this the frictional resistance offered to movement of the sash is not so great as to make the opening or closing 35 of the windows or their adjustment to any given position, too difficult. At the same time there are no sharp edges or corners contacting with the sides of the groove, so that wear is not objectionable. It will further be noted that the 40 points of juncture of the portions 14 with the bent-over portions of the wings are located well within the planes of the flattened sides of the grooves, so that the thrusts on the portions 14 extend in an inward angular direction with respect to the flattened sides of the grooves. Thus 45 the springiness of the metal is more effectively exerted.

It is to be understood that the particular cross-sectional shape of the tubular portion may vary, the important features being the overlapping of the free edges with freedom for movement relative to one another, the limited rubbing contact of non-sharp, smooth surfaces with the sides of the grooves, and the location of the juncture of the portions 14 with the bent-over portions

of the wings substantially within the planes of the flat sides of the grooves.

Metals having the springiness and weather resistance of the order of bronze may be substituted for the bronze, such, for example, as stainless steel and duralumin.

The free edges of the overlapping portions may be folded over or seamed as indicated, so as to present no sharp edges.

I claim:

1. For a window, the combination with the frame jambs, of a sliding sash having a groove in each side member which opens toward the adjacent jamb, and a combined sash balance, guide member and weather strip at each side of the window, which strips are substantially co-extensive with the height of the jambs, said strips being composed of springy material having a flat base portion for attachment to the jamb and a pair of semi-cylindrical-like portions projecting laterally therefrom to form a longitudinally extending tubular part which projects into the adjacent sash groove, said semi-cylindrical-like portions slidingly overlapping each other whereby to exclude the weather and to compensate for expansion and contraction of the sash, and the diameter of the tubular portion being normally greater than the

distance between the sides of the adjacent sash groove.

2. The combination of claim 1 wherein the diameter of the tubular portion is less than the depth of the sash groove.

3. For a sliding window sash having a guide groove in the edge face of each side member, a combined sash balance, guide member and weather strip composed of springy sheet material formed with a flat base or jamb engaging portion and a pair of semi-cylindrical-like sash groove engaging portions projecting laterally therefrom, said semi-cylindrical-like portions being arranged to slidingly overlap each other to form a resilient, closed, tube-like sash guide.

4. A combined sash balance, guide member and weather strip made from an elongated piece of springy sheet material, the side portions of said piece being bent back along a central area to provide a longitudinally extending base portion and being reversely bent and also curved to form a pair of cooperating semi-cylindrical-like portions projecting laterally from the base portion, said semi-cylindrical-like portions being slidingly overlapped to form a resilient, closed tube-like guide portion.
